UNITED STATES PATENT OFFICE.

EDWARD H. MILLER, OF NEW YORK, N. Y.

DESIGN FOR A BRACELET.

57,702.

Specification for Design. Patented Apr. 26, 1921.

Application filed October 11, 1920. Serial No. 416,321. Term of patent 7 years.

To all whom it may concern:

Be it known that I, EDWARD HENSHAW MILLER, a citizen of the United States, residing in New York, in the county and State of New York, have invented a new, original, and ornamental Design for a Bracelet, of which the following is a specification, reference being had to the accompanying drawing, forming part thereof.

Fig. 2 is a side view of the same, showing the parts as coiled when in use.

I claim:—

The ornamental design for a bracelet as shown.

EDW. H. MILLER.
